UNITED STATES PATENT OFFICE.

CALVIN DAVID PAXSON, OF CLEVELAND, OHIO.

METAL CROSS-TIE AND RAIL-FASTENING.

No. 796,858.

Specification of Letters Patent.

Patented Aug. 8, 1905.

Application filed November 22, 1904. Serial No. 233,836.

To all whom it may concern:

Be it known that I, CALVIN DAVID PAXSON, a citizen of the United States, and a resident of Cleveland, in the county of Cuyahoga and State of Ohio, have invented a new and Improved Metal Cross-Tie and Rail-Fastening, of which the following is a full, clear, and exact description.

This invention relates to metal cross-ties for railroads, and has for its object to provide novel details of construction for a metal cross-tie that afford great strength for a tie of minimum weight, adapt the tie to resist strain in every direction, and give it a broad bearing upon the road-ballast; and a further object is to provide a novel rail-clamping device which releasably secures track-rails in position on the cross-tie, properly spaced apart.

The invention consists in the novel construction and combination of parts, as is hereinafter described and claimed.

Reference is to be had to the accompanying drawings, forming a part of this specification, in which similar characters of reference indicate corresponding parts in all the figures.

Figure 1 is a perspective view showing the improved cross-tie in position on a road-bed and a track-rail held upon the cross-tie by a novel rail-clamp. Fig. 2 is a transverse sectional view of a track-rail and a partly-sectional side view of a portion of the improved cross-tie, the improved rail-clamp appearing in full and broken lines, the section being defined by their regular line 2 2 in Fig. 1. Fig. 3 is a plan view of an end portion of the improved cross-tie. Fig. 4 is an enlarged perspective view of a bolt-supporting holder-block that is a detail of the invention. Fig. 5 is a perspective view of an adjustable clamping-block employed. Fig. 6 is a side view of a rail-clamp and integral bolt, showing an improved nut thereon, the bolt being broken away between its ends. Fig. 7 is a perspective view of the nut for the clamping-bolt. Fig. 8 is an enlarged transverse sectional view of a track-rail, a longitudinal sectional view of the improved cross-tie whereon the track-rail is seated, taken on the line 8 8 of Fig. 1, and a side view of the improved rail-clamping means employed; and Fig. 9 is an end view of the improved cross-tie.

The improved cross-tie is formed of metal in elongated plate form, as shown at 10 in the drawings. The upper side of the cross-tie body is longitudinally channeled at several

points suitably spaced apart, as shown at *a* in Figs. 1, 3, and 9, leaving ribs *b* that are parallel and extend the entire length of the tie-body. Integral with the tie-body 10 a preferably central V-shaped flange 10^a is formed on the lower side thereof, extending the full length of said body, and it will be seen that the ribs *b* and depending flange 10^a greatly stiffen the cross-tie and adapt it to support heavy weight without breaking. Near the opposite side edges of the tie-body 10 and at a suitable distance from each end of the same rectangular openings *c c'* are formed therethrough, as shown in Figs. 1, 2, and 8.

For each end of the tie-body 10 a clamping-block 11 is provided, that is loosely engaged within the opening *c*, which is nearest the end of the tie. The clamping-blocks 11 being alike, a description of one will answer for the two provided for the cross-tie, and, as is clearly shown in Fig. 5, each block 11 consists of a flat, preferably rectangular, base-plate, from which centrally projects a hook member 11^a, integral with the base-plate and having the nose 11^b thereon extended laterally toward one side edge of the base-plate, as is shown in Figs. 1, 2, and 5.

The space between the openings *c c'*, near each end of the tie-body 10, is such as will dispose the opposite side edges of the base-flange 12^a on a track-rail 12 to overhang the nearest transverse edges of these openings when said track-rail is seated upon the cross-tie. The relative proportions of details of each clamping-block are such that the clamping members 11^a 11^b on the base-plate 11 may be loosely passed up through the opening *c*, near one end of the cross-tie, and when the base-plate contacts with the lower side of the latter the hook-nose 11^b, which projects in the direction of the corresponding opening *c'*, will be seated upon the base-flange 12^a of a track-rail 12, that is introduced between said openings *c c'* and is thus disposed transversely on the cross-tie.

A clamping-bolt 13, having an elongated body threaded at one end and bent at a right angle near the opposite end, so as to produce a short upright member 13^a thereon, is formed with a laterally-offset head 13^b on the upper end of the upright member 13^a. The head 13^b is passed up through the opening *c'* when the rail 12 is to be clamped upon the cross-tie body 10, and the body of the bolt is disposed lengthwise in contact with the lower

surface of the tie-body, having such length as will permit its threaded end portion 13^c to project beyond the end of the cross-tie toward which the bolt trends.

A holder-block 14, which is grooved, as at *d* in one side face, receives an end of the cross-tie body 10 and when in place extends transversely thereon, as is shown in Fig. 1. The groove *d* is intersected by another groove *d'*, that is formed in the lower wall, which defines the groove *d*, this groove *d'* receiving the depending flange 10^a when the holder-block 14 is mounted upon the end of the tie-body 10. A transverse perforation *e* is formed in the holder-block below the groove *d* at a point which permits the threaded end 13^c of the bolt 13 to be passed outward therethrough when the holder-block is mounted upon the end of the cross-tie body, as is clearly shown in Fig. 8. A nut 15 is mounted upon the portion of the bolt end that projects outside of the holder-block 14, and, as shown in Figs. 1 and 2, the offset head 13^b on the upright member 13^a of the bolt 13 is seated upon the base-flange 12^a of the track-rail 12 when parts are assembled for securing the track-rail upon the cross-tie.

It will be seen that when the clamping-bolt and its members are disposed with regard to the cross-tie, base-flange 12^a, and holder-block 14, as shown and described, the clamping adjustment of the nut 15, which pulls the head 13^b of the bolt upon the upper side of the base-flange 12^a, will force the opposite edge of the base-flange beneath the hook-nose 11^a of the clamping-block 11 and bind the track-rail securely on the cross-tie. Provision is made for preventing the reverse turning movement of the nut 15 on the bolt end 13^c, consisting in the formation of a longitudinal groove *g* in the threaded end portion of the bolt and a corresponding channel *g'* in the nut across its thread, this channel also extending across the end wall of the nut, which in service is in contact with the holder-block 14. The groove in the bolt-body is continued across the end of said bolt, so that a substantially Z-shaped channel is provided in the nut and bolt when the nut is adjusted so that the groove therein is opposite the groove in the bolt-threads. After the nut 15 is screwed upon the bolt end, so as to draw the bolt-head forcibly into engagement with the base-flange of the track-rail and the channels in the bolt and nut are disposed oppositely, a keeper in the form of a wire strand *g* is inserted into these channels and bent at the ends, so as to enter the transverse grooves in the nut and bolt end, which will secure the nut from turning on the bolt.

Obviously the means for holding the track-rail at one end of the cross-tie, as described, are to be duplicated for the other end of the same, thus securing two track-rails properly spaced apart on the cross-tie.

The upright members 11^a of the two clamping-blocks employed for each cross-tie may be gaged in thickness so as to afford more or less space between their faces that are below the nose members 11^b, and thus be adapted to space apart the rails to conform with the gage of the track.

The construction of the cross-tie with a longitudinal flange 10^a depending from its lower side at or near the transverse center of the tie-body adapts the road-ballast A to securely hold the cross-ties of improved construction stably on the road-bed.

Having thus described my invention, I claim as new and desire to secure by Letters Patent—

1. A cross-tie having a flat body and two spaced openings therein, a clamping-block having a hook member that projects up through one opening, stationary therein, a bolt having an angularly-bent end and head thereon passed up through the other opening, the head and hook member bearing oppositely on the base-flange of a track-rail, and means for drawing upon the bolt for forcing the head against the base-flange.

2. A T-shaped cross-tie having a plate-like body, two spaced openings in said body near each end, a clamping-block projected upward through one opening at each end of the tie and having a hook member, and means for drawing the base-flange of a track-rail into engagement with the hook member on each clamping-block.

3. A T-shaped cross-tie and rail-clamping device, comprising a plate-like tie-body having two spaced openings near each end, two clamping-blocks each having a hook member projected up from a flat base and passed upward through one opening at each end of the tie-body, two like clamping-bolts, each bent near one end thereof forming an upright member, an offset head on the upper end of each upright member, a thread on the opposite end of each clamping-bolt, a transversely-channelled holder-block mounted on each end of the tie-body, the holder-blocks each having a perforation through which passes the threaded end of one clamping-bolt, and a nut screwed on each bolt end and bearing upon a respective holder-block.

4. The combination with a track-rail, of a plate-like tie-body having two spaced openings therein near one end and between which the track-rail seats on the tie-body, a clamping-block having a hook member projected up through one opening that is nearest to the end of the tie-body and an integral base-flange which bears upon the lower side of the tie-body, said hook member bearing upon the base of the track-rail near one side edge thereof, a clamping-bolt having an upright member thereon near one end, said member having an offset head thereon passed up through the other opening in the tie-body

and bearing upon the rail-base near the other side edge thereof, the bolt having a thread on its remaining end, a channeled holder-block receiving in its channel one end of the tie-body and having a perforation through which the threaded end of the bolt passes, and a nut screwed on said end and bearing on the holder-block whereby the rail is clamped between the bolt-head and hook-nose of the

clamping-block and also clamped upon the cross-tie body.

In testimony whereof I have signed my name to this specification in the presence of two subscribing witnesses.

CALVIN DAVID PAXSON.
